Francis C. Kuebler, ATTORNEY

UNITED STATES PATENT OFFICE.

DAVID WILLIAM RIPLEY, OF FRESNO, CALIFORNIA, ASSIGNOR TO SUN-MAID RAISIN GROWERS ASSOCIATION, OF FRESNO, CALIFORNIA.

RAISIN CLEANER AND CAPPER.

Application filed May 8, 1924. Serial No. 711,817.

To all whom it may concern:

Be it known that I, DAVID WILLIAM RIPLEY, a citizen of the United States, and resident of Fresno, in the county of Fresno and the State of California, have invented a new and useful Improvement in Raisin Cleaners and Cappers, of which the following is a specification.

My invention relates to a machine for washing, cleaning and capping raisins.

In the art as now practiced in taking the cap stems off of raisins it is usual to make them bone dry and then apply friction which breaks the cap stems off. Raisins which are soft and cling together en masse are incapable of being properly capped or washed by the existing art. The object of my invention is to wash, cap and dry raisins in one operation. Other objects will be hereinafter set forth.

I accomplish these objects by means of the device hereinafter described and illustrated on the accompanying drawing, in which Figure 1 is a side view of the washing and capping device. Figure 2 shows a top fractional view of the concave screen, the screen roller and a screen. In said drawing I have shown a rigid frame 3, in which I have suspended a cylinder 4, which cylinder is covered with screen wire mesh. A hollow shaft 5, is attached at two opposite ends of frame 3, on an incline. Journals and bearings 6 and 7 are adapted to carry the cylinder so it can rotate around the hollow shaft. Stops or thrust bearings 8 and 9 are attached to shaft 5 to keep the cylinder on the bearings 6 and 7. It is here noted that while I have shown a cylinder (4) of uniform diameter and positioned on an incline to a horizontal line, the same results may be accomplished by using a conical cylinder and setting the axis on a horizontal line as the object I wish to accomplish by this construction is that raisins deposited in the higher end of the cylinder will gravitate to the other end as the cylinder is rotated. The cylinder shown in the drawing is rotated by means of a motor 10, driving a cog wheel 11, attached to the end of the cylinder. Any other equivalent driving or rotating mechanism may be substituted. The funnel 13 attached to the frame is adapted to direct the flow of the raisins into the cylinder. It is here noted that both ends of the cylinder are open, the upper end for receiving the raisins

and the opposite end for discharging them. Shaft 5 is hollow for the purpose of introducing water into the interior of the cylinder. This water is disposed of by a sprinkling system which is shown on the drawing to consist of an auxiliary pipe 14 having a plurality of nozzles 15 positioned to direct a spray to the bottom of the cylinder. The roughened line 16 on the bottom of the cylinder is to indicate a mass of raisins in the bottom of the cylinder and the lines 17 extending from the nozzles indicate the water spray. Under the cylinder is a fixed screen 20, the base of which describes a plurality of cylindrical concavities 21, positioned with the cups upward. In each concavity, and concentric therewith, is a rotatable screen covered cylinder which rotates in the direction shown by arrows 23, the object being to roll the raisins between the fixed screen 20 and the screen cylinders. The cylinders in the drawing are rotated by means of the motor 25, and a belt or chain 26 which rotates the plurality of cylinders simultaneously. The drawing shows that the cylinders 22 and the fixed screen 20 are suspended from beams 27 which incline at approximately the same angle from the perpendicular as the incline of the under part of cylinder 4. While I have shown the assembly of 85 rotatable screens and concave screens directly under the large cylinder 4, this arrangement is to conserve space only, as they may be positioned for the same purpose elsewhere.

At the lower end of the concave screen is an ordinary shaker screen 28, to which is imparted a shaking movement when the device is in operation, by means of a connecting rod 29, pivoted to the shaker at one end and at the other end to an eccentric 30, on one of the screen rollers. A pan 40 adapted to catch the water which passes through the screen cylinder 4, is attached under said cylinder, and the water thus drained is 100 emptied at a spout 41. The spokes 18 and 19 are intended to connect the hubs 6^a and 7^a of bearings 6 and 7, with the inside surface of the large cylindrical screen.

In operating this device, the raisins, which may be dry, moist, separated or en masse, are placed in the interior of cylinder 4, where they are agitated by being rolled over the interior screen surface of cylinder 4 as it is rotated, and while thus agitated a spray 110

of water is showered on the raisins which washes them and tends to dissolve the masses so that the raisins are separated. The water thus used runs through the screen and is 5 drained off. When the raisins reach the lower end of the screen they are dropped to the sheet screen 20 where they are fed between the concave screens and the screen rollers. This creates a friction which re- 10 moves the cap stems. The screen rollers rotate rapidly enough to give the raisins a centrifugal motion which, with the agitation further dries them. It is here noted that the space between the perimeter of the 15 roller and the inside of the concave screen can be adjusted, and while four concavities and corresponding rollers are shown on the drawing the number can be varied. The raisins are then passed over the shaker 28 20 which functions to further dry them and to separate them from small loose particles which may have adhered through the preceding operations. Experiments have shown that the operation as thus conducted washes 25 the raisins and while moist or wet the cap stems are readily removed. The screens for covering drums, rollers and for other uses herein described, may be wire mesh, perforated sheets of metal in which the perforations are smooth or rough or other equivalent of a screen. It is specifically herein noted that for the screens described, roughened surfaces can be substituted.

Having described my invention I claim as 30 new and ask for Letters Patent:

1. In a device of the character described, the combination of moist means for separating masses of raisins into individual

raisins in combination with a roller having a roughened periphery and a pan having a 40 concavity therein approximately concentric with the roller, and means for feeding the integral moist raisins between the roller and the concave portion of the pan, substantially as described.

2. In a device of the character described, the combination of means for washing raisins, two roughened surfaces spaced apart, and means for passing the raisins while wet between said two roughened surfaces, substantially as described.

3. In a device of the character described, means for washing raisins in combination with two screen surfaces constructed and adapted so that one will move a spaced distance from the other, and means for feeding raisins while wet between said surfaces, substantially as described.

4. In a device for removing cap stems from moist and wet raisins, the combination of screens arranged so the faces thereof are a spaced distance apart, and means for moving one of said surfaces, means for washing the raisins, and means for feeding the moist and wet raisins between said surfaces.

5. A roller having a wire screened outer surface, a pan having a concavity therein formed of wire screen and positioned concentric with the roller a spaced distance from the inside surface of the concavity, means for rotating the roller means for moistening and washing raisins and means for feeding the moist raisins between the roller and the concavity in the pan.

DAVID WILLIAM RIPLEY.
